COMBINED PITCHER AND COVER THEREFOR

Ernest L. Crider, Shelby, Tenn.
(3949 Hedgerow Cove, Memphis, Tenn. 38109)

Filed Feb. 17, 1969, Ser. No. 15,817

Term of patent 14 years

Int. Cl. D7—01

U.S. Cl. D44—21

FIG. 1 is a top plan view of a combined pitcher and cover therefor, showing my new design;

FIG. 2 is an exploded perspective view;

FIG. 3 is a front elevational view;

FIG. 4 is a side elevational view of the cover member;

FIG. 5 is a top plan view of the pitcher member;

FIG. 6 is a side elevational view of the combined pitcher and cover; and

FIG. 7 is an enlarged scale partial sectional view on line VII—VII of FIG. 3.

I claim:

The ornamental design for a combined pitcher and cover therefor, as shown.
